UNITED STATES PATENT OFFICE.

VINCENT G. APPLE, OF DAYTON, OHIO.

ARMATURE CONSTRUCTION FOR DYNAMO-ELECTRIC MACHINES.

1,224,518.

Specification of Letters Patent.

Patented May 1, 1917.

Application filed November 19, 1914. Serial No. 872,959.

To all whom it may concern:

Be it known that I, VINCENT G. APPLE, a citizen of the United States, residing at Dayton, in the county of Montgomery and State of Ohio, have invented certain new and useful Improvements in Armature Construction for Dynamo-Electric Machines, of which the following is a specification.

My invention relates to armature constructions for dynamo electric machines and a method of making same.

One of the objects of my invention is to provide a new and useful method of placing current inducing conductors on armature cores of dynamo electric machines.

Another object of my invention is to generally improve armature structures.

Other and further objects of my invention will become readily apparent, to persons skilled in the art, from a consideration of the following description when taken in conjunction with the drawings, wherein—

Figure 1 is a longitudinal central section through the armature core.

Fig. 2 is a rear end elevation, showing for the purpose of illustration four pairs of armature conductors in place.

Fig. 3 is a front elevation of the armature core.

Fig. 4 is a transverse section on line 4—4 of Fig. 1.

Fig. 5 is a transverse section on line 5—5 of Fig. 1.

Fig. 6 shows the armature conductors stacked and positioned ready to be pushed into the axially extending perforations or apertures in the core.

Fig. 7 shows a fragment of the commutator and a part of the conductor for cross connecting the armature bars together and with the commutator.

Fig. 8 shows an armature conductor, such as a copper rod or bar, bent upon itself into hair pin form, prior to forming it into the wish bone shape shown in Fig. 9.

Fig. 9 shows a bar conductor in proper shape to be inserted within respective apertures in the armature core.

Fig. 10 is a perspective view of an insulating member for two adjacent conducting bars occupying the same aperture.

Fig. 11 is a perspective view of the commutator connector, a fragment of which is shown in Fig. 7.

55 In all the views the same reference char-

acters are employed to indicate similar parts.

When a series of windings, each comprising a pair of integral conductors of a bar wound armature have heretofore been applied to an armature core, as when a pair of said conductors are made into the wish bone type, it has been required that the core have a smooth face or be provided with grooves between adjacent teeth, so that such formed conductors could be laid in place around the periphery of the core. In such a construction not any of the armature core intervenes between the conductor and the field magnet.

Prior to my invention, such integral plural bar form of conductors have not been applied to armature cores of the Wenstrom or ironclad type, which are pierced axially, at frequent circumferential intervals, near the periphery for reception of the conductors. In such armatures, in which bar conductors have heretofore been used, one or more single bars have been placed in each perforation and separable connectors have been used at the ends of the bars to cross connect said straight bar conductors. Such a construction involves considerably more labor and introduces largely increased internal resistance, when compared with my method of procedure.

Some of the principal advantages of bar windings, generally, are reduction in the number of wires; ease of manipulation; the stability of the structures; the relatively low resistance; the more constant electro-motive force and relatively small internal loss. But these advantages are largely offset, in the usual bar wound armatures where the conductors are directly presented and exposed to the magnetic field, by the induced eddy currents that are impressed upon each conductor bar. Such currents are never present, however, in ironclad armatures, wherein the conductor bars are placed within or embedded in the body part of a laminated core, as when they are included within the axial apertures near the periphery of the core.

My invention, therefore, provides a bar wound armature without the need of separable cross connections at the ends of the bars and in which the conductors are within closed apertures passing axially through the core, a structure that has previously been

impossible of attainment within the teachings of the prior art.

In the single exemplification which I have chosen for the purpose of illustrating my invention, 12 is the usual armature shaft; 13 is the commutator thereon; 14 is the core comprised of a number of thin, soft iron, preferably insulated, disks held in place on the armature shaft by relatively heavier 10 disks 15, and 16. The core is axially perforated at circumferential intervals, as at 17, said perforations being relatively wider in radial planes than in circumferential planes for the accommodation of the two 15 conductors to be contained therein. Each conductor 18, is composed of a bar of metal such as copper, as shown in Fig. 8, first bent upon itself into two parallel limbs or legs 19 and 20 giving a general hairpin shape to the 20 coil. The limb or leg 19 is shorter than the leg 20 and each of the legs is slit at its free end, as at 21 and 22, respectively. The conductor 18, after being bent in the form shown in Fig. 8, is subsequently bent into the form 25 shown in Fig. 9. Each of the legs 19 and 20 is laterally deflected from the yoke portion of the structure 23, and each of the legs is bent so that the parallel surfaces through its longer transverse dimensions are radial 30 to its axis or in radial planes corresponding with the slots in the armature core within which they are to be placed.

The conducting bars may conveniently be insulated in the apertures which they occupy 35 by an insulating member 25, which may be made of a strip of fiber, or the like, bent into the shape resembling the figure 8, providing openings 26 and 27 for adjacent bars in the same slot. In Fig. 5, near the upper part of 40 the transverse center of the figure, two conducting bars are shown in the openings 26 and 27 of the insulating member 25, and other insulating members are shown, in the apertures, in the same figure, ready for the 45 reception of the conducting bars. This form of insulator provides an insulating wall between each conducting bar and the surrounding core, and also between adjacent conducting bars, in a one piece structure.

50 When it is desired to place the conductors in their respective apertures, within the core of the armature, the insulating members 25 are preferably first placed in the apertures in the core and the insulating ring 55 30, which also has perforations registering with those in the core, being held in place by the washer 16, but the insulating ring 31 is not in the position in which it is shown in Fig. 1 at this time. If preferred the insulating members may first be placed on the 60 respective conducting bars before they are pushed into the apertures in the core.

The armature conductors or conducting bars necessary for a given armature, are now 65 stacked or placed in nesting relation, as

shown in Fig. 6, and the insulating ring 31 may then be placed over the conductors so as to position them in place substantially the same distance apart they will be when they are in the respective perforations in 70 the armature core. The longer ends of the conductors are now inserted in the outer apertures 26 of the insulating member 25, which apertures are farthest removed from the center of the core and the entire number 75 of conductors are pushed into the core from the rear end thereof until the shorter conductors 19 confront the apertures 27 in the insulating member. The entire number of conductors are now pushed into the core until they occupy the positions substantially as shown in Fig. 1, and the ring 31 is brought to its place. Each of the conductors is now surrounded by a fiber lining provided by the insulating member 25 and these 80 members 25, pass entirely through the core and the insulating rings 30 and 31. An insulating ring 32, preferably of fiber, is now placed on the commutator end between the conductors 19 and 20, and another insulating ring 33, which is sufficiently large to pass over the end of the shaft 12 is placed in front of the washer 16.

The commutator connecting members 34, consist each of a strip of conducting material, preferably such as hard drawn copper, which is provided with two leaf members 35 and 36, joined together as at 37. The part 37, of each of these connectors, is inserted in a slot 38, made in each of the commutator bars 13', wherein it is soldered or brazed.

The short leaves 35, of the connector 34, are adapted to be secured in the slots 21 of the shorter conductor bars 19, and the longer leaves 36 of the connector are adapted to be secured in the slots 22 of the outer, longer arms 20 of the conductors. It will be observed that the leaves 35 of the connector are deflected in one direction and the leaves 36 are deflected in the opposite direction from the radial plane occupied by the connecting portion 37. Before the commutator 13 is placed in position on the armature all of the leaves 35 may be pressed in one direction, and the ring 39 slipped over the depressed leaves thereby to insulate the two conductors 35 and 36 from each other, or the ring may be split and slipped in place.

Before the commutator 13 with its connectors 34 is placed upon the shaft the connectors are bent in the respective positions so that they will register with the slots 21 and 22 made in the forward ends of the conductors 19 and 20 so that each of the ends 35 and 36 will register with its respective slot and will be easily entered therein when the commutator is pushed upon the shaft to its proper position.

After the leaves 35 and 36 of the connec-

tors have been properly soldered to the respective conducting bars 20 and 19 the armature is ready for operation.

An armature made in accordance with my 5 method of construction is practically indestructible; the space occupied by conductors at the ends of the core is relatively very small; and the time and labor required to place the conducting members in position in 10 the core is substantially negligible.

The integral rear ends joining the conductor bars 19 and 20 may be taped or otherwise insulated, to prevent contact of the adjacent yokes, one with the other, as shown 15 in Fig. 1.

While I have herein shown my invention applied to a four pole armature, it is evident that other forms of armature, having a greater or less number of poles, may be constructed in accordance with the said invention, and while I have disclosed one embodiment of my invention, it is manifest that departure may be made therefrom in the arrangement and disposition of the parts, 25 within the scope of the appended claims.

Having described my invention, what I claim is:—

1. The method of wiring a dynamo electric machine member having axially extending openings disposed around its peripheral portion with a plurality of independent conductors each having parallel legs for insertion in circumferentially spaced openings, which consists in stacking all of the 30 conductors in regular order with the legs arranged for registry with the openings in the member, and relatively moving said member and the stacked conductors axially to insert said conductors into said openings.

40 2. The method of wiring a dynamo electric machine member having axially extending openings, disposed around the peripheral portion thereof, which consists in shaping a plurality of independent conductors 45 with parallel legs for insertion in circumferentially spaced openings, stacking all of said conductors in regular order with the ends of two different bars arranged for registry with each opening in the member, 50 and relatively moving said member and the stacked conductors axially to insert said conductors into said openings.

55 3. The method of wiring an armature core having a plurality of axially extending perforations disposed around the peripheral

portion thereof, which consists in shaping a corresponding number of conductor bars into hairpin formation, stacking all of the bars in overlapped relation with their ends arranged for registry with the perforations, 60 maintaining the bars in stacked relation and relatively moving said armature core and said conductors axially into said perforations.

4. The method of wiring an armature 65 core having a plurality of axially extending openings disposed around its peripheral portion, which consists in shaping a number of conductors equal to the number of openings into hairpin formation, stacking all of said 70 conductors in regular order with the ends of two different conductors arranged for registry with each opening, and relatively moving the stacked conductors and said armature core axially to insert said conductors into 75 said openings from one end thereof.

5. The method of wiring an armature core having a plurality of axially extending openings disposed around the peripheral portion thereof, which consists in shaping a 80 plurality of conductors into hairpin formation, stacking said conductors in regular order with their ends arranged for registry with said openings, threading a perforated insulating ring over said conductors to hold 85 them in stacked position, and relatively moving said stacked conductors and said armature core axially to insert said conductors into said openings.

6. The method of wiring a dynamo 90 electric machine member having axially extending openings disposed around its peripheral portions with conductors having parallel legs for insertion in circumferentially spaced openings, which consist in stacking all of the 95 conductors in regular order with the legs arranged for registry with the openings in the member, securing said conductors in their stacked relationship by means of an insulating member, and relatively moving said 100 stacked conductors and said member axially to insert said conductors into said openings.

In testimony whereof I hereunto set my hand in the presence of two subscribing witnesses.

VINCENT G. APPLE.
